LOCOMOTIVE SMOKEBOX STEAM
INJECTION DRAFT CONTROL

Paul Willis, Blue Island, Ill., assignor of one-third to Edmund P. Kelly, Chicago, and one-third to Grant Roth, Evanston, Ill.

Application July 11, 1946, Serial No. 682,946

6 Claims. (Cl. 110—147)

1

My invention relates to improvements in draft controls for locomotive boilers and the like and has for one object to provide automatic means for controlling the intensity of the draft in consonance with variation in boiler pressure.

As is well known, the draft in a locomotive is induced by the discharge of exhaust steam through the exhaust nozzle. The higher the velocity of the exhaust steam, the stronger the draft. Usually the size of draft nozzle is selected for maximum capacity or at least for some point not too far below maximum capacity. As a result when the engine is operating at lower capacity less exhaust steam passes through the nozzle, the draft drops and there is difficulty keeping the engine hot.

I propose to associate with the nozzle means which will insure adequate draft conditions even at low engine output. I propose to do this by means of a butterfly valve or other suitable constricting means which will obstruct though not prevent the discharge of steam through the exhaust nozzle. This butterfly valve or other obstructing member when in the closed position will reduce the effective nozzle area and so maintain a high velocity even though the engine is working in its lower ranges.

When the engine is working at or toward maximum capacity, a hot fire must be kept up and high boiler pressure is needed. However, if the nozzle constriction remains effective, maximum exhaust will give inordinately high blast velocities and excessive draft to cause the fire to burn out too rapidly.

I propose therefore that when the boiler pressure reaches a certain predetermined point, the butterfly valve will be automatically opened to increase the effective nozzle area and so prevent undue increase of exhaust blast velocities. The operation being entirely automatic frees the engineer from watching or compensating for changes in engine operation, and one purpose of my invention therefore is to provide automatic means which will in consonance with boiler conditions and engine operation adjust draft conditions to suit changes in engine operation.

My invention is illustrated more or less diagrammatically in the accompanying drawings, wherein:

Figure 1 is a longitudinal section of the locomotive smoke box and adjacent boiler parts;

Figure 2 is a front elevation of the boiler with parts broken away;

Figure 3 is a section on an enlarged scale along the line 3—3 of Figure 1;

Figure 4 is a section along the line 4—4 of Figure 3;

Figure 5 is a section on an enlarged scale along the line 5—5 of Figure 2; and

2

Figure 6 is a diagrammatic plan view of the exhaust nozzle.

Like parts are indicated by like characters throughout the specification and drawings.

1 is a boiler having a head 2, and a plurality of fire tubes 3 discharging into the smoke box 4. 5 is a stack discharging outwardly from the smoke box; 6 an exhaust nozzle in line with the stack adapted to discharge exhaust steam from the engine through the stack. 7 is a screen adapted to prevent the discharge of large cinder particles from the fire box through the fire tubes and out of the smoke box through the stack. 8 is a ring mounted on the discharge end of the nozzle 6 held in place by bolts 9. Lugs 10 on the ring are apertured to rotatably support shafts 11 and 12 which carry a butterfly or bridge member 13 which when in a plane parallel with the ring 8, restricts though not entirely closing the effective area of the exhaust nozzle 6. When positioned parallel to the axis of the nozzle, the butterfly valve member exerts substantially no constricting effect. The shaft 11 is mounted in bearing 12, extends outwardly through the wall of the smoke box 4 and is rotatably mounted at its outer end in the bracket 14 mounted on a plate 15 on the outer wall of the smoke box 4. Plate 15 carries a cylinder 16 in which is reciprocably mounted a piston 17, having a connecting rod extending outwardly through the packing gland 18 to support a link 19 pivoted on a lever 20 fixed on the shaft 12. The rod 21 is slidable in a bearing sleeve 22 on the plate 15, and has pivoted at one end a link 23 which is also pivoted on the lever 20. A spring 24 is compressed between the opposite end of the bearing 22 and a cap 25 adjustably threaded on the rod 21 and provided with a lock nut 26.

27 is a steam pipe adapted to supply steam from the boiler to the cylinder 6. It is associated with an automatic control valve illustrated in Figure 3. The pipe 27 communicates with the low pressure chamber 28 in the control valve and a pipe 29 brings boiler pressure from the boiler 45 to the high pressure chamber 30 in the control valve. 31 is a valve seat ring member interposed between chambers 28 and 30 adapted to be engaged by a plug valve 32, the latter having a tapered portion 33 to engage the tapered portion 50 34 of the valve seat 31. The valve 32 travels within the packing gland 33, packing 34 and packing nut 35 to make a steam tight fit. 36 is a yoke forming a part of the automatic valve assembly apertured at 38 to guide the reciprocation 55 of the adjustable member 39 which carries a spring seat 40, the spring 41 being compressed between the end of the yoke and the spring seat. When the pressure in the boiler reaches a certain maximum determined by the adjustment 60 of the tension in the spring 41, boiler pressure

unseats the plug valve 32 and since movement of the plug valve as it leaves the seat 33 does not change the pressure relationships, the valve immediately assumes a wide open position when the pressure is sufficient to overcome the tension of the spring. This permits steam at boiler pressure to pass through the pipe 27 into the cylinder 16, overcoming the spring 24 and rotating the butterfly to the dotted line position shown in Figure 5 where no constriction of the exhaust jet occurs. When boiler pressure drops below a predetermined point, the spring 41 closes the plug valve and shuts off steam from the boiler. The spring 24 can then rotate the butterfly to the horizontal position, as indicated in Figure 5, returning the piston 17 to the starting position, the bleeder ports 42 permitting such movement, and the exhaust is constricted. The stop pins 43 on the bracket 14 are engaged by the lever 20 at each end of its excursion and limit its movement to either full open or full restriction positions.

I claim:

1. In combination with a boiler having a smoke box, flues and an exhaust stack, an exhaust steam nozzle adapted to discharge exhaust steam through the stack to induce a draft, means adapted to restrict the effective opening of the exhaust nozzle and means responsive to boiler pressure and operative only when a maximum pressure is reached for rendering said nozzle restricting means ineffective.

2. In combination with a boiler having a smoke box, flues and an exhaust stack, an exhaust steam nozzle adapted to discharge exhaust steam through the stack to induce a draft, means adapted to restrict the effective opening of the exhaust nozzle and means responsive to boiler pressure and operative only when a predetermined maximum boiler pressure has been reached for rendering said nozzle restricting means ineffective, said means including a cylinder, a piston therein, a connection between one side of the piston and the boiler and a mechanical connection between the piston and the opening restricting means.

3. In combination with a boiler having a smoke box, flues and an exhaust stack, an exhaust steam nozzle adapted to discharge exhaust steam through the stack to induce a draft, means adapted to restrict the effective opening of the exhaust nozzle and means responsive to boiler pressure and operative only when a maximum pressure is reached for rendering said nozzle restricting means ineffective, said means including a cylinder, a piston therein, a connection between one side of the piston and the boiler and a mechanical connection between the piston and the opening restricting means, a spring loaded valve exposed to boiler pressure and means for adjusting it to permit opening of the valve and actuation of the piston only when the boiler pressure reaches a predetermined maximum.

4. In combination with a steam boiler and an exhaust nozzle adapted to induce a draft therefor, means for restricting the effective area of the nozzle, actuating means therefor including a cylinder, a piston mounted for reciprocation therein, a steam connection between the boiler and one side of the piston, yielding means for resisting movement of the piston under steam pressure and tending to return the piston to starting position thereagainst, a mechanical connection between the piston and the nozzle restricting means so disposed that the restricting

means is in the closed position when the piston is at one end of its excursion and in the open position when the piston is forced by steam pressure to the other end of its excursion, a spring loaded valve associated with the steam connection adapted to be set to yield when predetermined boiler pressure is reached to open the steam connection to cause piston movement responsive to steam pressure.

10 5. In combination with a steam boiler and an exhaust nozzle adapted to induce a draft therefor, means for restricting the effective area of the nozzle, actuating means therefor including a cylinder, a piston mounted for reciprocation therein, a steam connection between the boiler and one side of the piston, yielding means for resisting movement of the piston under steam pressure and tending to return the piston to starting position thereagainst, a mechanical connection between the piston and the nozzle restricting means so disposed that the restricting means is in the closed position when the piston is at one end of its excursion and in the open position when the piston is forced by steam pressure to the other end of its excursion, a spring loaded valve associated with the steam connection adapted to be set to yield when predetermined boiler pressure is reached to open the steam connection to cause piston movement responsive to steam pressure, 20 said valve being set for wide open and completely closed positions only.

30 6. In combination with a steam boiler and an exhaust nozzle adapted to induce a draft therefor, means for restricting the effective area of the nozzle, actuating means therefor including a cylinder, a piston mounted for reciprocation therein, a steam connection between the boiler and one side of the piston, yielding means for resisting movement of the piston under steam pressure and tending to return the piston to starting position thereagainst, a mechanical connection between the piston and the nozzle restricting means so disposed that the restricting means is in the closed position when the piston is at one end of its excursion and in the open position when the piston is forced by steam pressure to the other end of its excursion, a spring loaded valve associated with the steam connection adapted to be set to yield when predetermined boiler pressure is reached to open the steam connection to cause piston movement responsive to steam pressure, 30 said valve being set for wide open and completely closed positions only, and positive means for limiting the excursion of the nozzle restraining means between open and shut positions.
